FIG.1

FIG.2

FIG.3

FIG. 1 is a perspective view of an electric toaster embodying my new design, the undisclosed sides being substantially similar in appearance;

FIG. 2 is a plan view of the electric toaster, the bottom thereof being substantially flat and plain; and

FIG. 3 is a fragmentary rear view, drawn to a reduced scale, of the electric toaster.

The buttons are shaded to illustrate progressively darkening tones of brown.

The dominant features of my design reside in the por-

tion shown in full lines, the others being shown fragmentarily for convenience of illustration.

I claim:

The ornamental design for an electric toaster, as shown and described.
